APPARATUS FOR MAKING CONCRETE STRUCTURAL SHAPES

Albert Henderson, Pittsburgh, Pa.

Application November 9, 1955, Serial No. 545,892

8 Claims. (Cl. 25—121)

The apparatus of this application is particularly suitable for making various precast reinforced concrete building units such as the I-beams, channels, Z-beams, T-beams and H-columns disclosed in my co-pending patent application Serial No. 545,891, filed November 9, 1955, and can also be used in making rectangular concrete units.

In the units disclosed in the said application, there are a great number of variations in the heights, widths, flange thicknesses, web thicknesses, and I here disclose a simple apparatus for their manufacture.

In the accompanying drawings,

Figure 1 is a side elevation of one of my hinged lattice frame mold side walls, in its closed and smallest position;

Fig. 2 is a side elevational view and said mold side wall, in a fully open position;

Fig. 3 is a sectional view of the mold side wall shown in Fig. 2, on the line III—III.

Fig. 4 is an elevation of a larger adjustable hinged lattice frame mold side wall;

Fig. 5 is a plan view of a connected pair of mold side walls shown in Fig. 4;

Fig. 6 shows a section through an assembly of mold side walls similar to those shown in Figs. 1 and 4, adjusted to less than full height;

Fig. 7 shows assembled mold side walls extended to full height;

Fig. 8 shows a section through metal fillers for extending the core mold side walls;

Fig. 9 shows a section through a double adjustable core for a channel-shaped floor slab;

Figs. 10 and 11 each shows sections through one of the floor slab mold side walls of Fig. 9;

Fig. 12 shows a section through a double adjustable core and a hollow concrete unit formed thereby, and

Fig. 13 is a sectional view of a modified form of the cores shown in Fig. 6.

Referring to Figs. 1, 2 and 3, and adjustable form 1 having side frames each of which is made up of two pairs of two oppositely-disposed angle bars 2 that serve as corner bars for the form and are movably connected by hinged struts or links 3. At each end of the angles 2, spaced holes 4 are provided, and a strut-like brace member 5 is bolted through these holes, to regulate the required height of the mold side frame. This height will be in increments of one inch, and precast concrete units with 2" variations in height can be accommodated. A plywood or steel plate filler 6 can be clipped to struts 3 or the angles 2. Adhesive tape 7 can be used to cover the prepared gap 8 which allows the upper angle to move downward and release the mold side wall from contact with the casting.

A mold side wall 9 in Fig. 4 has upper and lower angles 10 and hinged struts or links 11. Holes 12 are for securing a strut-like tie member such as 5 which holds the mold side wall to the required height.

The adjustable mold side walls 1 and 9 are made in 10-ft. lengths and have connecting angles 4a as in Figs.

2

1, 2 and 3, and 13 in Fig. 4. The mold side wall shown in Fig. 1 is smaller than mold side wall 9 shown in Fig. 4.

Figs. 5 and 6 show mold side walls 1 abutting mold side walls 9. The side walls 9 are slidable and are held by adjusting struts 14. When the side walls 9 are moved in opposite directions, the distance between them is changed.

Fig. 6 shows the assembled mold side walls 1 and 9 resting on a flat casting bed 15. This view shows the mold side walls 1 acting as cores for the webs of the flanged concrete units. The assembled mold side walls are shown as in the smallest position possible, but can be extended vertically a considerable height. End mold walls 16 are shaped to suit the shape of the concrete unit made in the mold.

To operate these adjustable assembled molds, the side walls are set to the desired height, and all the form walls are clamped together against mold end walls 16. After the concrete has gained sufficient strength, the mold walls 1 and 9 are released by sliding them past each other and then pulling the mold sides en masse ahead on the casting bed 15 and setting up the mold side walls again. It would be possible to obtain several pours a day with each set of mold side walls. The mold side walls can be collapsed as shown, or they can be tapered as shown in Fig. 13. After removing the mold side walls ahead, the cast concrete units are allowed to rest where cast until they are strong enough to be picked up and removed to a stock pile.

Fig. 7 shows the mold side walls 1 and 9 extended to full height and extensions 17 can be added to gain still greater height. A larger sized mold side wall may be necessary to make the use of extensions 17 unnecessary. In order to extend core mold side walls 1, extension plates 18 shown in Fig. 8 can be bolted to the core angles through plates 19. To make a Z-beam, blocking 20 is used to blank out the diagonally opposite flanges of the I-beam cavity, and if a channel beam is required, then two directly opposite flanges of the I-beam cavity are blanked out. If a T-beam is required, the two lower flanges are blanked out, but leaving the web to extend the full height of the unit. Fig. 8 shows core extension plates to suit the flange extensions of the beams.

Figs. 9, 10 and 11 are all members of a mold for making channel-shaped concrete floor or roof slabs of different widths and heights and different leg thicknesses. A mold 21 has upper and lower corner angles 22 that are secured by adjusting struts 23 for horizontal movement in providing the desired width of core, and adjusting struts 24 regulate the height of the core 21. Struts 23 and 24 are secured to the same corner angles 22, and fillers 25 are held in place by tapes 26. The mold side walls 27 are assembled a short distance away from the slab core 21 and all form walls resting upon a bed 28, and adjustable struts 29 are secured to angles 30. If the mold side walls 27 are too short, extensions 31 will be bolted to the upper angles 30. This apparatus as shown in Figs. 9, 10 and 11 provides a simple means for obtaining channel-shaped concrete floor or roof slabs of different widths and depths. A plywood or steel plate 32 is shown resting on the upper adjusting struts 23. Adhesive tapes 33 cover the small gaps between the plate 32 and the upper angles 22. The tapes keep concrete from packing into the gaps and preventing release of the core. A metal core 32a is used when concrete slabs require cross ribs for bracing the legs of the slab. When the mold 21 is released, it slips past and under the core 32a. Only the bottom of the slab concrete cross ribs rest on the mold 21. A loose tie 32b pulls core 32a down when the slab is lifted out of the mold.

Fig. 12 shows a four-way collapsible core 35 having

corner angles 36 connected to slidably adjustable struts 37. A rubber sleeve 38 prevents concrete from getting into the gaps 39. This core is useful in making hollow precast concrete units shown at 40.

Fig. 13 shows a modified tapered core member 41 which will allow the core to be extracted without collapsing the core 41. In this type of core, extension pieces 18 as shown in Figs. 7 and 8 are not necessary. Corner angles are bolted to ties 43, and angles 42 are moved similar to angles 10 in Fig. 5, which has ties 14 similar to the ties 43. The gap between angles 42 is covered by rubber 44 which completely covers the core 41 and is tucked in between the core 41 and the mold wall 9. The angles 42 are moved vertically by adjusting struts 45. Bolts 46 passing through these struts and members 11 clamp the taper core 41 to the mold side walls 9. Hand holes can be provided in the angle 10, so that the bolts 46 can be reached. This type of core can be moved both horizontally and vertically. A pin 47 is provided for insertion in holes in the core 41, for vertical adjustment, and an extension 48 provided when needed for greater height.

The rubber or elastic material 44 which may be absorbent or non-absorbent is detachably secured to the core member 41. This type of elastic cover lessens suction and it slightly pulls away from the core 41 and gradually loosens its contact with the green molded unit when the core 41 is extracted.

This elastic cover stretches and allows the core 41 to be extracted sooner than if the core had direct contact with the freshly molded unit, thus making it possible to place the mold side walls into quicker cycles of operations.

I may attach turnbuckles to oppositely-disposed mold side walls and use the turnbuckles to provide horizontal forward and backward movements of the two oppositely-disposed mold side walls including their cores.

To make extra deep precast reinforced concrete flanged shapes, I can superimpose the hinged lattice frame mold side walls, including hinged lattice frame cores. These superimposed frames can be bolted together. In all cases, the core moves independently of the straight hinged lattice frame mold side walls.

The concrete shapes use standardized reinforcing steel cages, and I propose to set spaced-apart reinforcing steel cages on the casting bed, and after releasing the hinged lattice framed mold side walls from the green concrete shapes, I pull the mold side walls endwise until they are positioned between the spaced reinforcing steel cages, such as the reinforcement shown in my copending application, after which the molds are filled with concrete. The elastic cover for the core is detachable and is used to reduce suction as the elastic cover sticks to the concrete unit and gradually frees itself from the unit.

I claim as my invention:

1. Mold apparatus for making concrete shapes of elongated form, comprising a frame-work having two pairs of corner bars spaced in relatively opposed relation to form space for a mold cavity, struts, pivotally connected at their ends to the bars of each pair, each pair of bars and its struts forming a collapsible mold side-frame and the struts in each side-frame being parallel to one another and foldable relative to their bars, brace members independent of said struts and connected to the bars of each pair and releasably holding them at desired distances apart, to thereby vary the effective width of the side-frames, and filler members supported at the inner faces of the side frames, at opposite sides of the said space.

2. Mold apparatus for making concrete shapes of elongated form, comprising a pair of mold side frames that are spaced apart to provide space for a mold cavity, each frame including upper and lower members that are

connected by parallel struts which are pivoted to the said members, whereby the said members are movable toward and from each other, for expansion and contraction of the side-frame, brace members non-parallel to the said struts and independent thereof, and means for adjustably connecting the brace members to the said upper and lower members, at various angular positions relative to the struts to thereby hold the said members at desired distances apart.

3. Apparatus as recited in claim 2, wherein the side frames are slidably supported on a casting bed, and a plurality of pairs of similarly formed side frames are supported on the bed, and the upper and lower frame members of one pair are respectively connected by horizontal struts that are pivotally connected to the upper and lower frame members of the next adjacent pair of side frame members, to thereby provide for adjustment of the space widths between the various side frames.

4. Mold apparatus as recited in claim 2, wherein the said upper and lower mold frame members are connected to other upper and lower side-frame members that extend vertically beyond the uppermost and lowermost first-named mold frame members, and are connected together by hinged struts, the said extended portions serving as

25 mold walls that extend higher and lower than the first-named mold side frames, to thereby form a mold cavity of I-beam shape.

5. Mold apparatus as recited in claim 4, wherein those mold side-frames which are of the lesser height are adjustable toward and from the other side frames, to vary the thickness of a beam web.

6. Mold apparatus as recited in claim 4, wherein the second-named frame members are adjustable vertically independently of the first-named side frame members.

7. Mold apparatus for making concrete, that comprises four corner mold frame bars in rectangular formation, two series of struts that respectively pivotally connect each corner frame member to the next two adjacent corner frame members, the struts of each series being

40 parallel with one another, for collapsing and expansion movements of their associated corner frame bars, mold wall elements bridging the spaces between the corner frame bars, and means independent of said struts, for releasably holding the bars at various rigidly set relative spacings.

8. Mold apparatus for elongated shapes, that comprises a pair of spaced mold side-frames each of which includes upper and lower members pivotally connected to struts for vertical expansion and contraction, a second mold side-frame that has upper and lower members connected to the first-named upper and lower members, of one of the first-named side-frames at the inner side thereof, and being of shorter vertical dimension than the first-named side frames, struts pivotally connecting the second-named frame members, for expansion and contraction vertically, means independent of the struts for releasably holding the various upper and lower side frame members at various vertical spacings, and means forming side walls for a mold cavity, at the inner sides of the said 60 side frames.
